CUTLERY DEVICE

John W. Hunt, Pontiac, Mich., and William A. Hunt, Chicago, Ill.; said William A. Hunt assignor to said John W. Hunt

Application June 12, 1953, Serial No. 361,366

4 Claims. (Cl. 30—142)

The present invention relates to a novel cutlery device of the type wherein the blades and other instruments thereon are enclosed in a combination handle and housing and are adapted to be swung out of said housing into their operative positions.

More particularly the present invention relates to a pocket cutlery device which includes the conventional blades, screwdriver, awl, can opener, bottle opener, and the like and also includes therein a novel nail clipper.

It is, therefore, one object of the present invention to provide a socket cutlery device which includes any desired combination of a conventional blade or blades and tools and a novel clipper device.

Another object of the present invention is to provide a novel pocket cutlery device including a nail clipper which may be swung out of the housing of said device into its operative position.

A further object of the present invention is to provide a pocket cutlery device including a housing, a nail clipper mounted in said housing, an operating arm for said nail clipper, and recesses within said housing to receive said nail clipper and operating arm when folded into their inoperative positions within said housing so as to provide a pocket cutlery device having smooth surfaces with no projections therefrom to catch on the inside of a pocket or handbag when said device is carried therein.

Other objects of this invention will appear in the following description and appended claims, reference being had to the accompanying drawings forming a part of this specification wherein like reference characters designate corresponding parts in the several views.

In the drawings:

Fig. 1 is a front view of one embodiment of the present invention showing the position of the blades and nail clipper within the combination handle and housing.

Fig. 2 is a sectional view taken along the line 2—2 of Fig. 1 in the direction of the arrows.

Fig. 3 is a top view of the pocket cutlery device of Fig. 1 with a portion thereof broken away and the nail clipper swung out into operative position.

Fig. 4 is an end view of the pocket cutlery device of Fig. 1 with the nail clipper in operative position.

Fig. 5 is a fragmentary view of the nail clipper of Fig. 4 showing a modification of operating arm and pin.

Before explaining the present invention in detail, it is to be understood that the invention is not limited in its application to the details of construction and arrangement of parts illustrated in the accompanying drawings, since the invention is capable of other embodiments and of being practiced or carried out in various ways. Also, it is to be understood that the phraseology or terminology employed herein is for the purpose of description and not of limitation.

One embodiment of the present invention is shown in Figs. 1—5. Fig. 1 is a front view of this embodiment of the present invention. The pocket cutlery device 20 comprises the combination handle and housing 21, the blades 22 and 23, and the nail clipper 24. As shown in

2

Fig. 1, the blades 22 and 23 are pivoted into carrying position within housing 21 and the nail clipper 24 is pivoted into the housing with the jaws enclosed in the recess 25 in the end of housing 21.

5 The housing 21 includes the upper plate 26 and the lower plate 27. These plates are assembled in spaced parallel relationship and enclose therebetween the remaining parts of the pocket cutlery device.

Fig. 2 is a top view of the pocket cutlery device of Fig. 1 with the top plate 26 (Fig. 1) removed and the blade 23 swung out into operative position. The spring 27 is provided to engage the notch 28 in the end of blade 23 to hold the blade in its operative position. The blade 23 pivots about a rivet or similar device 29 as does also blade 22. The spring 27 is mounted at the back of housing 21 by the rivets or similar devices 30 which pass through the upper and lower plates 26 and 27. A similar spring (not shown) is provided below spring 27 for blade 22.

The nail clipper 24 is pivotally mounted by rivet or similar device 31 which passes only through the lower plate 27 so as not to interfere with the positioning of blade 23 for storage within housing 21 (Fig. 1).

As shown in Fig. 3 the pivoted end of nail clipper 24 is provided with the notch 32 and the spring 27 is provided with the extension 33 to engage the notch 32 when the nail clipper is swung out to its operative position.

Referring now to Fig. 4 the nail clipper 24 comprises an upper flat spring member 34 and a lower flat spring member 35 joined together at one end. The free end of the upper member 34 has the downwardly projecting jaw 36 formed thereon. The lower member 35 is bent downwardly at 38 and thence upwardly to form the generally semicircular depression 39 and terminates in the jaw 40. The pin 41 passes upwardly through a hole provided in the depression 39 and through a hole provided in the upper member 34. The head 42 is provided on pin 41 and one end of an operating arm 43 is pivoted in the slot 44 provided near the upper end of pin 41. The operating arm 43 is provided with the struck out portion 45 which serves as a fulcrum when the lever is in the operating position shown in Fig. 4. It is believed apparent that the jaws 37 and 40 of the clipper 24 are forced together when the free end of arm 43 is depressed.

Referring to Fig. 3 it can be seen that the struck out portion 45 of arm 43 provides the space 46 in the arm so that the arm may swing over the end of pin 41. Referring again to Fig. 4 the top of pin 41 is chamfered as at 47 so that the operating arm may be swung to the right over the end of pin 41 until the struck out portion 45 of arm 43 engages the unchamfered portion 48 of the top of pin 41. Since the pin 41 is free to rotate the arm 43 may then be turned until it overlies the upper spring member 34 as shown in Figs. 1 and 2. The struck out portion 45 engages the top of pin 41 and serves to hold the arm 43 in spaced relation from the member 34 so that (as shown in Fig. 1) when the clipper 24 and blade 23 are pivoted into the housing 21 the blade 23 is received between the arm 43 and the member 34. Also, in Fig. 1 the recess 49 is provided in the bottom of upper plate 26 to receive arm 43. The recess 49 is shown in dotted lines in Fig. 3 and is so formed as to hold the free end of arm 43 slightly out of housing 21 as shown in Fig. 2 so that the arm 43 may serve as a grip to swing the nail clipper out of the housing.

Fig. 5 is a fragmentary view of the nail clipper of Fig. 4 showing a modified operating pin and arm which may be used in the nail clipper of the pocket cutlery device of Figs. 1—4 within the scope of the present invention.

In Fig. 5, pin 41a is provided with the head 42a on the lower end thereof and the upper end of the pin 41a

is cut away from both sides to provide the extension 49 thereon. A transverse hole is provided in this extension 49 to receive the end of an operating arm 43a. The end of operating arm 43a has the convoluted finger 50 formed thereon which is received in the hole provided in the extension 49 of pin 41a. Arm 43a is thus affixed to pin 41a so as to enable said arm to swing over the top of said pin.

The struck out portion 45a is provided on arm 43a adjacent the finger 50. As shown in Fig. 5, this struck out portion 45a serves as a fulcrum for operating arm 43a when said arm is in its operative position. It is believed apparent that by depressing the free end of arm 43a, when in its operative position as shown in Fig. 5, the jaws of the nail clipper will be urged together 15 to cut anything placed therebetween.

The operating arm 43a may be swung to the right (Fig. 5) over the upper end of pin 41a. The pin 41a is free to rotate so that the arm 43a may then be turned to overlie flat spring member 34.

A flat portion 51 is provided on the convoluted finger 50 so that the biasing action of the clipper aids in holding operating arm 43a in its inoperative position.

From the above description it can be seen that we have provided a novel pocket cutlery device which includes the usual blades or tools and a novel nail clipper.

We have also provided a novel pocket cutlery device including a nail clipper wherein said nail clipper and the operating arm therefor are received within recesses provided in said cutlery device so as to provide a pocket cutlery device having smooth contours so that no projections are left to catch on a pocket or handbag when said device is carried therein.

In the above description where we have made reference to blades mounted in our pocket cutlery device, it is to be understood that we contemplate substituting therefor any other desired tool, such for example as screwdrivers, awls, bottle openers, and the like without departing from the spirit, scope and purpose of our invention.

Having thus described our invention we claim:

1. In a pocket cutlery device including a housing and a plurality of blades pivotally mounted in said housing to swing out of said housing into operative position, the provision of a nail clipper mounted in said housing and comprising upper and lower flat spring members joined at one end and bent inwardly toward each other at the opposite ends to form cutting jaws, said lower member bent downwardly at a point inwardly from said jaw end and thence upwardly toward said jaw end to form a semicircular depression in said lower member, a pin passing upwardly through said depression and through said upper member, a head on said pin engaging the lower surface of said lower member, an operating arm pivotally affixed near its end to a slot near the upper end of said pin above said upper spring member so that said arm may swing over the top of said pin and lie back parallel to said upper member in an inoperative position, said nail clipper being pivotally mounted within said housing near the center thereof by a pin through the joined ends of said flat spring members so that said clipper may be swung out of said housing into an operative position, a recess in one end of said aforementioned housing to enclose the jaws of said clipper when the clipper is pivoted into said housing, and a recess in said housing to partially receive said operating arm of said clipper when said clipper is pivoted into said housing and said operating arm is in its inoperative position leaving a portion of said operating arm protruding from said housing to serve as a gripping means to pivot said clipper out of said housing toward the operating position of said clipper.

2. In a pocket cutlery device including a housing, a plurality of blades pivotally mounted in said housing to swing out of said housing into operative position, and a blade spring for each of said blades mounted within

said housing to engage said blades and retain them in operative and inoperative position, the provision of a nail clipper mounted in said housing and comprising upper and lower flat spring members joined at one end and bent inwardly toward each other at the opposite ends to form cutting jaws, said lower member bent downwardly at a point inwardly from said jaw end and thence upwardly toward said jaw end to form a semicircular depression in said lower member, a pin passing upwardly through said depression and through said upper member, a head on said pin engaging the lower surface of said lower member, an operating arm pivotally affixed near its end to a slot near the upper end of said pin above said upper spring member so as to swing over the top of said pin and lie back parallel to said upper member in an inoperative position, said nail clipper being pivotally mounted within said housing near the center thereof and adjacent one of said aforementioned blade springs by a pin through the joined ends of said flat spring members so that said clipper may be swung out of said housing into an operative position, a projection on said adjacent blade spring to engage a notch provided on the pivoted end of said nail clipper and retain said nail clipper in its operative position, a recess in one end of said aforementioned housing to enclose the jaws of said clipper when the clipper is pivoted into said housing, and a recess in said housing to partially receive said operating arm of said clipper when said clipper is pivoted into said housing and said operating arm is in its inoperative position leaving a portion of said operating arm protruding from said housing to serve as a gripping means to pivot said clipper out of said housing toward the operating position of said clipper.

3. In a pocket cutlery device including a housing and a plurality of blades pivotally mounted in said housing to swing out of said housing into operative position, the provision of a nail clipper mounted in said housing and comprising upper and lower flat spring members joined at one end and bent inwardly toward each other at the opposite ends to form cutting jaws, said lower member bent downwardly at a point inwardly from said jaw end and thence upwardly toward said jaw end to form a semicircular depression in said lower member, a pin passing upwardly through said depression and through said upper member, a head on said pin engaging the lower surface of said lower member, an operating arm having a convoluted finger on one end thereof, said convoluted finger engaging in a hole near the upper end of said pin above said upper spring member so that said arm may swing over the top of said pin and lie back parallel to said upper member in an inoperative position, said nail clipper being pivotally mounted within said housing near the center thereof by a pin through the joined ends of said flat spring members so that said clipper may be swung out of said housing into an operative position, a recess in one end of said aforementioned housing to enclose the jaws of said clipper when the clipper is pivoted into said housing, and a recess in said housing to partially receive said operating arm of said clipper when said clipper is pivoted into said housing and said operating arm is in its inoperative position leaving a portion of said operating arm protruding from said housing to serve as a gripping means to pivot said clipper out of said housing toward the operating position of said clipper.

4. In a pocket cutlery device including a housing and a plurality of blades pivotally mounted in said housing to swing out of said housing into operative position; the provision of a nail clipper mounted in said housing and comprising upper and lower flat spring members joined at one end and bent inwardly toward each other at the opposite ends to form cutting jaws, said lower member being bent downwardly at a point inwardly from said jaw end and thence upwardly toward said jaw end to form a semicircular depression in said lower member, a pin pass-

ing upwardly through said depression and through said upper member, a head on said pin engaging the lower surface of said lower member, an operating arm pivotally affixed near its end to said pin above said upper spring member so as to swing over the top of said pin and lie back parallel to said upper member in an inoperative position, said nail clipper being pivotally mounted within said housing near the center thereof by a pin through the joined ends of said flat spring members so that said clipper may be swung out of said housing into an operative position, a recess in one end of said aforementioned housing to enclose the jaws of said clipper when the clipper is pivoted into said housing, and a recess in said housing to partially receive said operating arm of said clipper when said clipper is pivoted into said housing and said operating arm is in its operative position leaving a portion of said operating arm protruding from said housing to serve as a gripping means to pivot said clipper out

10 of said housing toward the operating position of said clipper.
